RIDGE VENTILATOR

James H. McDerment, Cleveland, Ohio, assignor
to The Swartwout Company, Cleveland, Ohio,
a corporation of Ohio

Application September 22, 1936, Serial No. 102,000

1 Claim. (Cl. 98—42)

This invention relates to ventilators of the type known as ridge ventilators, which are adapted to be used in connection with elongated openings in roofs and to extend therealong for a considerable distance. This application is in some respects a continuation in part of my application, Serial No. 727,306, filed May 24, 1934 now Patent No. 2,072,461, patented March 2, 1937.

The general object of the invention is to provide means for supporting the side members or side baffles of a ventilator of the character referred to in such manner as to anchor their bases securely while enabling them to be quickly and conveniently removed, as for purposes of renewal, repair, or painting.

I accomplish the foregoing object in and through the construction and arrangement of parts shown in the drawings, wherein Fig. 1 represents a transverse sectional view of a ventilator constructed in accordance with my invention, the said view corresponding substantially to the line 1—1 of Fig. 2; Fig. 2 a central longitudinal sectional view through so much of a ventilator of the type referred to as will be necessary to an understanding of my invention; Fig. 3 a detail in section through the lower end of one of the side members or baffles and the subjacent portions of the flashing member and cross frame, the parts being separated; Fig. 4 a detail in elevation of the lower end of the side member or baffle shown in Fig. 3; and Fig. 5 a detail in section corresponding to the line 5—5 of Fig. 4.

Describing the various parts by reference characters, 10 and 11 denote spaced portions of a roof between which an elongated ventilation opening A is formed. These roof portions are shown as provided each with an inclined surface 10^a, 11^a, respectively, said surfaces converging upwardly.

The ventilator shown herein comprises generally flashing plates each secured to the inclined surfaces 10^a and 11^a, side baffles extending upwardly from said flashing plates, a ridge cap interposed between the upper ends of the side baffles, and a damper interposed between the upper ends of the side baffles and the opening formed between the upper ends of the flashing plates, together with transverse frames for supporting the ridge cap, the upper ends of the side baffles, the lower ends of the side baffles and the damper-raising and lowering mechanism.

12 denotes the flashing plates, the same providing between their upper ends an outlet for the air circulating upwardly through the opening A. The upper ends of these members are folded upon

themselves, as shown at 13, providing a double thickness of metal where the damper is supported when closed. 14 denotes a plurality of transverse straps extending between the upper ends of the flashing plates and having downwardly inclined ends 14^a by which they are secured to said plates. At similarly spaced intervals are transverse frames, each comprising opposed downwardly and outwardly inclined lower end portions 15 terminating in vertically extending stakes 16. From the upper ends of the portions 15 extend the vertical side portions 17. From the upper ends of the side portions 17 extend the upwardly and inwardly inclined portions 18, the upper ends of the portions 18 being connected by 19 the transverse upper end portions 19. The lower end portions 15 are secured to the flashing members 12 and to the downwardly inclined ends 14^a of the transverse straps 14 by means of bolts 20.

21 denotes a ridge cap having downwardly and outwardly inclined lower end portions 21^a supported by the inclined portions 18 of the cross frames and projecting beyond and overhanging the sides of the opening provided between the upper ends of the flashing members.

22 denotes the side baffles the lower ends of which rest upon the flashing plates 12 and the upper ends of which are projected inwardly or toward each other and extend above the lower ends of the ridge cap, cooperating with the latter 30 to prevent access of rain, sleet, etc. into the opening formed between the upper ends of the flashing members.

The lower end of each side baffle is provided with drain openings 22^a, said openings being provided immediately below loops which are formed by providing vertically spaced slots 23 above said drain openings and pressing inwardly the metal between said slots, as shown at 24. The loops and the drain openings of each side baffle will be 40 spaced as to correspond with the spacing of the cross frames.

The upper ends of the baffles are supported from the cross frame by means of straps 25, each having a downwardly and outwardly inclined lower end 25^a which is secured to the adjacent inclined portion 18 of a cross frame by means of a bolt 26, which bolt also extends through the portion of the ridge cap supported by said cross frame. The upper end of each strap is detachably connected to the upper end of a side baffle by means of a screw bolt 27 extending through the upper end portion of the side baffle and through an upwardly and inwardly inclined end portion 25^b of the strap. The upper end of each side

baffle is bent upon itself as shown at 22^b and this end may engage the upper end of the portion of the strap 25^b therebelow.

The upper transverse members 19 of the cross frames support the damper operating mechanism, the said mechanism being shown, described and claimed in my aforesaid application Serial No. 727,306. This mechanism, also shown in part herein, comprises generally brackets 28 to 10 which are pivotally secured links 29 in turn pivotally connected to angle members 30 carried by the damper 31, the damper being in the shape of a flat inverted V having downward turned ends 31^a extending beyond the tops of the flashing members. Connected to the links 29 or to a suitable number of them are levers 32, the upper ends of which are connected to a connecting link or links 33. One of the levers 32 carries a pulley 34 at its upper end. The damper 31 is 20 provided with an opening 35 adjacent to which is a pulley 36 carried by suitable bracket members 37. Also connected to one of the levers 32 by means of a pivoted link 38 is a cable 39, which passes from its point of attachment to 25 the link 38 around pulleys 40, 34 and 41 and thence over the pulley 36 and downwardly through the opening 35, to a place conveniently accessible for operation of the ventilator.

In Figs. 1 and 2, the damper is shown in 30 closed position. In order to raise the same, the operator merely pulls upon the cable 39, which results in swinging the damper longitudinally while moving it upwardly into the dotted line position shown in Fig. 1.

35 By the manner of constructing the cross frames and the side baffles, the latter may be securely supported in place by the former, but

can be quickly and conveniently removed, should occasion require. It is only necessary to unscrew the bolts 27 which connect the upper ends of the side baffles to the straps 25, whereupon the baffles may be lifted from their seats upon the flashing members, for inspection, repair, or painting, after which they may be as conveniently replaced. Furthermore, the location of the drain openings allows them to be formed by the same operation whereby the loops for the stakes 19 are formed.

Having thus described my invention, what I claim is:

The combination in a ridge ventilator, of a pair of upwardly converging flashing plates extending along opposite sides of a roof opening and secured thereto, longitudinally spaced transverse frames having downwardly and outwardly divergent lower ends secured to the said plates and having their lowermost ends upturned to 20 provide stakes, each of said frames having opposed portions extending upwardly from the inclined portions and having portions extending upwardly and inwardly from the upper ends of the last mentioned portions, straps secured to 25 the said upwardly and inwardly inclined portions of said transverse frames, side baffles extending upwardly from the flashing plates and each of said baffles having above its lower edge a loop projecting inwardly therefrom and each having 30 its upper end detachably secured to said straps, the loops being formed by pressing inwardly portions of the said baffles adjacent to the bottom edges thereof and the stakes entering said loops, the said baffles being provided with drain 35 openings located below the said loops.

JAMES H. McDERMINT.
